CLAIM

The ornamental design for a tree step including an integrated shank, as shown and described.

DESCRIPTION

FIG. 1 is a perspective view of one embodiment of a tree step including an integrated shank showing my new design;

FIG. 2 is another perspective view of FIG. 1;

FIG. 3 is a front side elevational view of FIG. 1, the rear elevational view being a mirror image thereof;

FIG. 4 is a top plan view of FIG. 1;

FIG. 5 is a bottom plan of FIG. 1;

FIG. 6 is a left elevational view of FIG. 1;

FIG. 7 is a right elevational view of FIG. 1;

FIG. 8 is a perspective view of another embodiment of a tree step including an integrated shank showing my new design;

FIG. 9 is another perspective view of FIG. 8;

FIG. 10 is a front elevational view of FIG. 8, the rear elevational view being a mirror image thereof;

FIG. 11 is a top plan view of FIG. 8;

FIG. 12 is a bottom plan view of FIG. 8;

FIG. 13 is a left elevational view of FIG. 8; and,

FIG. 14 is a right elevational view of FIG. 8.

The broken lines shown in the figures are included for the purpose of illustrating environment and form no part of the claimed design.
